[57] **CLAIM**

The ornamental design for a housing for communication equipment, as shown and described.

DESCRIPTION

FIG. 1 is a top, front and right side perspective view of a housing for communication equipment showing our new design;

FIG. 2 is a top plan view thereof;

FIG. 3 is a front elevational view;

FIG. 4 is a bottom plan view;

FIG. 5 is a rear elevational view thereof; and

FIG. 6 is a right side elevational view, the left side elevational view being substantially a mirror image.

FIG. 2

FIG. 3

FIG. 4

FIG. 5

FIG. 6
